DESIGN FOR A SLIP

Samuel L. Freedgood, Long Beach, N. Y.

Application March 6, 1936, Serial No. 61,507

Term of patent 3½ years

To all whom it may concern:

Be it known that I, Samuel L. Freedgood, a citizen of the United States of America, residing in Long Beach, L. I., county of Nassau, and State of New York, have invented a new, original, and ornamental Design for a Slip, of which the following is a specification, reference being had to the accompanying drawing, forming part thereof,

Fig. 1 is a front view of a slip showing my new design.

Fig. 2 is a rear view of the slip shown in Fig. 1. The characteristic feature of my design resides in the relation of the two side points to the central point, giving the brassiere portion a half-star-like appearance as shown.

I claim:

The ornamental design for a slip substantially as shown and described.

SAMUEL L. FREEDGOOD.
